UNITED STATES PATENT OFFICE.

RAYMOND C. SPAULDING, OF MONTCLAIR, NEW JERSEY.

SIGNALING.

SPECIFICATION forming part of Letters Patent No. 716,301, dated December 16, 1902.

Application filed January 29, 1902. Serial No. 91,812. (No model.)

To all whom it may concern:

Be it known that I, RAYMOND C. SPAULDING, a citizen of the United States, and a resident of Montclair, in the county of Essex and State 5 of New Jersey, have invented certain new and useful Improvements in Signaling, of which the following is a specification.

My invention relates generally to signaling, and more specifically to a system in which a 10 sound-producing device and a light-producing device are controlled by a common operating means.

The object of my invention is to appeal to more than one sense when signaling and in 15 this way to render it more certain that the signal has been noticed and apprehended by the person or persons for whom it is intended. Its use will be readily understood in its application to an automobile, for example, as 20 more fully described hereinafter, where the intermittent sounding of the horn will be accompanied by a flash of light for each blast. This flash may be produced simultaneously 25 with the sounding of the horn, or a steady light may be extinguished momentarily every time the horn is sounded and relighted after each blast. For this purpose a separate light from the headlight or the latter itself may be used, according to circumstances.

30 In the drawings I have embodied my invention in several forms; but changes and modifications may of course be made within the scope of the claims.

In the said drawings, Figure 1 is a general 35 view of the elements embraced in the system applied to the horn of an automobile embodying my invention. Fig. 2 is a detail view, partly in section, of the bulb and adjacent elements shown in Fig. 1. Figs. 3 and 4 show 40 modifications of the system shown in Figs. 1 and 2. Fig. 5 shows a detail of Figs. 3 and 4. Fig. 6 shows an adaptation of my invention in connection with a steam-whistle.

Similar letters of reference indicate corresponding parts in the different views.

45 A represents a bulb which when compressed sounds the horn B in the usual manner by vibrating the diaphragm b', interposed in the passage b². This passage b² is provided with 50 a tube C, located between the bulb and the diaphragm, so as to divert part of the air to act upon the plunger c', the lower end c² of

which forms a movable electrode adapted to contact with the stationary electrode c³ when it is moved into its closed position by the 55 pressure of the air. The lower end of the tube C and adjacent elements may be incorporated in the box X.

The movable and stationary electrodes are both connected by means of the line-wires d' 60 and d², properly insulated, with the light d³, the latter of the two wires being connected with the battery D. It will now be readily understood that when the bulb A is compressed the air will produce the usual sound 65 in vibrating the diaphragm and will also move the plunger c' down so that its lower end c² will come in contact with the stationary electrode c³, thereby closing the circuit and producing a flash of the light at d³. The 70 plunger is returned to its normal position by the action of the spring c⁶ when the air-pressure ceases. This operation will be repeated every time the bulb is compressed, the horn 75 being sounded and the flash of light produced simultaneously.

When it is desired not to produce a flash of light, as in the day-time, the valve c⁵ is simply turned, thus preventing the passage of air through the tube C. In case it is desired to 80 have the light d³ steady it is only necessary to close the shunt-switch d⁵, thereby producing the desired result.

In Fig. 3 and 4 the reverse order is observed, the light being normally steady and intermittently extinguished whenever the movable electrode is brought out of contact with the stationary electrode by the action of the air. This is accomplished in this instance by making the tube C communicate with the closed 85 compartment E, provided at its lower end with the stationary electrode c³ and having its movable electrode c² attached to a flexible diaphragm e³, adapted to be inflated by the pressure of the air. The two electrodes are 90 properly insulated, and the passage of the movable electrode back to its normal position is facilitated by means of the spring e' in contact at all times with the movable electrode c², the line-wire passing through the insulation e² of the box E to the said spring, thereby 95 maintaining constant communication between the battery and said electrode.

In Fig. 6 is shown an adaptation in connec-

tion with a steam-whistle F, the steam passing through the pipe f^2 , having the valve f^2 interposed, being diverted through the small pipe f^3 to the reducing-valve f^4 , thence to the 5 movable electrode contained in the box f^5 , operating in the same manner as in the case of the construction shown in Figs. 1 and 2.

It is of course obvious that changes may be made within scope of the claims and that I 10 do not limit myself to the exact construction shown herein.

Having thus described my invention, what I claim is—

1. In signaling, the combination of a sound-producing device, actuated by fluid-pressure, an electric circuit, a light-producing device located in said circuit, a switch controlling the circuit and light-producing device, means for producing fluid-pressure to operate the 15 sound-producing device, and means whereby the said pressure operates the controlling-switch simultaneously therewith.

2. In signaling, the combination of a sound-producing device, actuated by fluid-pressure, an electric circuit, a light-producing device located in said circuit, a switch controlling the circuit and light-producing device, means for producing fluid-pressure to operate the 20 sound-producing device and means whereby the 30 said pressure closes the controlling-switch simultaneously therewith.

3. In signaling, the combination of a sound-producing device, actuated by fluid-pressure, an electric circuit, a light-producing device located in said circuit, a switch controlling the circuit and light-producing device, means for producing fluid-pressure to operate the sound-producing device, means whereby the 35 said pressure operates the controlling-switch 40 simultaneously therewith and means for operating the sound-producing device and the light-producing device independently of each other.

4. In signaling, the combination of a sound-producing device, actuated by fluid-pressure, an electric circuit, a light-producing device located in said circuit, a switch controlling the circuit and light-producing device, means for producing fluid-pressure to operate the 45 sound-producing device, means whereby the 50 said pressure closes the controlling-switch simultaneously therewith and means for op-

erating the sound-producing device and the light-producing device independently of each other.

5. In signaling, the combination of a horn, an electric circuit, a light-producing device located in said circuit, a fluid-operated switch controlling the circuit and light-producing device, a compressible bulb, for creating fluid-pressure to sound the horn, communicating with the latter, and means for diverting part of the fluid-pressure to operate the switch simultaneously with the sounding of the horn. 55 60

6. In signaling, the combination of a horn, an electric circuit, a light-producing device located in said circuit, a fluid-operated switch controlling the circuit and light-producing device, a compressible bulb, for creating fluid-pressure to sound the horn, communicating 70 with the latter, and means for diverting part of the fluid-pressure to close the switch simultaneously with the sounding of the horn. 75

7. In signaling, the combination of a horn, an electric circuit, a light-producing device located in said circuit, a fluid-operated switch controlling the circuit and light-producing device, a compressible bulb, for creating fluid-pressure to sound the horn, communicating with the latter, means for diverting part of the fluid-pressure to operate the switch simultaneously with the sounding of the horn, and means for sounding the horn and for operating the light-producing device independently 80 of each other. 85

8. In signaling, the combination of a horn, an electric circuit, a light-producing device located in said circuit, a fluid-operated switch controlling the circuit and light-producing device, a compressible bulb, for creating fluid-pressure to sound the horn, communicating with the latter, means for diverting part of the fluid-pressure to close the switch simultaneously with the sounding of the horn, and means for sounding the horn and for operating the light-producing device independently 90 of each other. 95

Signed at New York, in the county of New York and State of New York, this 24th day of January, A. D. 1902.

RAYMOND C. SPAULDING.
